UNITED STATES PATENT OFFICE.

GUSTAV KERNATS, OF CHICAGO, ILLINOIS, ASSIGNOR OF ONE-HALF TO FRED WISSINGER, OF CHICAGO, ILLINOIS.

CUTTER.

Application filed November 16, 1925. Serial No. 69,542.

The invention relates to cutters and more particularly to cutters employed to produce a plane surface on wooden blocks or blocks of other materials.

- 5 The invention is specially identified with the art of photo-engraving, where it becomes necessary to provide wooden blocks to which the zinc or copper plate is secured with plane surfaces.
- 10 It is an object of the invention to provide cutters with a large cutting edge whereby the life of the cutters is considerably enhanced.

A further object aims at providing cutters which may be reset to present new portions of the cutting edge to the material to be operated upon without necessitating adjustment of the cutter in the holding device.

- 20 A still further object aims at providing cutters which after a single adjustment in the holding device remain in such adjusted position and permit replacement of the operative portion of the cutter or resetting of 25 the same without necessitating adjustment of the cutter as a whole in its holding device.

With these and other objects in view the invention comprises the means described in 30 the specification, particularly pointed out in the claims forming a part thereof, and illustrated in the accompanying drawing, in which:

Figure 1 is a front view elevation of a 35 plurality of cutters secured in a holding device and constructed in accordance with my invention;

Figure 2 is a section on the line 3—3 of Figure 1;

40 Figure 3 is a front view of the operative portion of the cutter;

Figure 4 is a sectional plan view, the section being taken on line 5—5 of Figure 3; and

45 Figure 5 is a front view of a modified form of the cutter arrangement.

The cutter comprises a shank portion 16 which terminates in a knee 17 extending at an angle to the shank 16 and provided with 50 a bore 18 at the free end for the reception of the operative portion of the bit presently to be described.

The bit comprises a tubular portion 19 provided with a head 20 in the shape of a 55 frusto-cone, the head being cored out to

form a hollow chamber 21 tapering with increasing diameter toward the lower end to provide a cutting edge 22 of circular form. The chamber 21 leads at the other end into a vertical bore 22' which extends 60 through the tubular portion 19. The junction of the head 20 and the tubular portion 19 creates a seat 23 which fits onto the free end of the knee 17 and a screw 24 is introduced through the chamber 21 and is 65 threaded into the knee 17 to secure the bit to the knee 17.

In use, the shank 16 is introduced into the aperture 13 of the disk 10, and upon proper adjustment of the cutter, the set 70 screw 15 is tightened so as to secure the cutter in position. If, after considerable use, the portion of the cutting edge which slightly projects beyond the wheel 10, is worn out, and it becomes necessary to have 75 a new portion of the cutting edge presented to the material to be operated upon, then the screw 24 is loosened and the head 20 is slightly turned, whereupon the screw 24 is tightened. Further adjustment of the 80 cutter, however, is not necessary. If all of the portions of the cutting edge 22 have been used up and it becomes necessary to replace the bit, in such case, the screw 24 is again loosened, the bit 19 is removed and 85 replaced by a new cutter and secured to the knee 17. This exchange may be rapidly made without necessitating adjustment of the cutting device in the holder 10.

In Figure 5, a similar cutter is shown for 90 planing a horizontal surface. The holding device again comprises a disk 10 which holds a plurality of cutters 16^a comprising shank portions 18^a and knee portions 17^a to the free end of which my improved bit 95 20 is secured. The disk 10 is secured to the upper end of a vertical shaft 32 to which rotation is imparted in any appropriate or conventional way.

While the invention has been particularly 100 described in connection with photo-engraving, it is, of course, applicable to other arts and no limitation is intended as far as the use of the invention is concerned to which the same may be put. The drawings 105 disclose preferred embodiments of the invention, but various changes and alterations may be made, and it is, therefore, not my intention of limiting myself to the details of construction as shown, but to include all 110

2 variations, re-arrangements and alterations which fairly fall within the scope of the invention as set forth in the appended claims.

5 I claim:

1. A cutting device, including in combination, a disk having apertures therein, a bit holder secured in said apertures, and comprising a shank portion, and a knee 15 extending at an angle to said shank portion, and a circular bit adjustably mounted on said knee.
- 10

2. A cutting device, including in combination, a disk having apertures therein, a bit holder adjustably secured in said apertures and comprising a shank portion, and a knee extending at an angle to said shank portion, a circular bit mounted on said knee and a threaded element passing centrally through said bit and extending into said knee for adjustment on said bit. 20

In witness whereof I affix my signature.

GUSTAV KERNATS.
